UNITED STATES PATENT OFFICE

123,227

DESIGN FOR A REAR CAR OF A RAILWAY TRAIN

Oliver Edward Hyde, New York, N. Y.

Application June 1, 1940, Serial No. 92,752

Term of patent 14 years

To all whom it may concern:

Be it known that I, Oliver Edward Hyde, a citizen of the United States, residing in the city and county of New York, State of New York, have invented a certain new, original, and ornamental Design for a Rear Car of a Railway Train, of which the following is a specification, reference being had to the accompanying drawing forming a part thereof and in which:

Figure 1 is a perspective view of the rear car

of a railway train embodying my new design, and

Fig. 2 is a rear end elevation of the rear car of a railway train of the present design.

Both sides of the design are identical and accordingly only one side is illustrated, and the front end of the car is conventional.

I claim:

The ornamental design for a rear car of a railway train, substantially as shown and described.

OLIVER EDWARD HYDE.
